(57) **CLAIM**

The ornamental design for a topless storage bag as shown and described.

DESCRIPTION

FIG. 1 is a front perspective view of a topless storage bag showing my new design;

FIG. 2 is a rear perspective view thereof;

FIG. 3 is a top perspective view thereof;

FIG. 4 is an enlarged sectional front perspective view thereof;

FIG. 5 is another enlarged sectional front perspective view thereof; and,

FIG. 6 is an opposite side enlarged front perspective view thereof.

The evenly dashed broken lines depict the cut lines of the enlarged views and form no part of the claim. The broken lines in the drawings depict claimed stitching.
